CLAIM

The ornamental design for a pair of scissors, as shown and described.

DESCRIPTION

FIG. 1 is a front left-top perspective view of a pair of scissors, showing my new design;

FIG. 2 is a front plan view thereof;

FIG. 3 is a rear plan view thereof;

FIG. 4 is a left side plan view thereof;

FIG. 5 is a right side plan view thereof;

FIG. 6 is a top plan view thereof;

FIG. 7 is a bottom plan view thereof;

FIG. 8 is a front plan view thereof with the tools in retracted
position; and,

FIG. 9 is a perspective view showing the pair of scissors of
the claimed design in a folded state.
